UNITED STATES PATENT OFFICE.

FREDERICK W. MOORE, OF NEWARK, NEW JERSEY, ASSIGNEE TO MCKEEON COMPANY, OF BOSTON, MASSACHUSETTS, A CORPORATION OF MASSACHUSETTS.

MACHINE FOR FORMING DESIGNS IN FIBROUS SHEETS OR LAYERS.

1,070,511.

Specification of Letters Patent. Patented Aug. 13, 1913.

Application filed July 13, 1910, Serial No. 771,773. Renewed February 13, 1913. Serial No. 740,894.

To all whom it may concern:

Be it known that I, FREDERICK W. Moore, a citizen of the United States, residing in Newark, county of Essex, and State of New Jersey, have invented an Improvement in Machines for Forming Designs in Fibrous Sheets or Layers, of which the following description, in connection with the accompanying drawings, is a specification, like letters on the drawings representing like parts.

This invention relates to a machine for forming a design in the surface of a layer or sheet of felt or other fibrous material and has for its object to provide a machine with which portions of the surface of the sheet or layer may be removed to form a design which is sharply and clearly defined in fibrous layers or sheets composed of the same or different qualities or kinds of fiber. To this end, the machine is provided with a pattern having a series of recesses or openings which form molds for the component parts of the design, a rotatable support or backing member for said pattern, a pressure roller between which and the pattern is fed the fibrous sheet or layer, said pressure roller cooperating with the pattern to force portions of one surface of the fibrous sheet or layer into the molds, and a knife whose cutting edge is interposed between the pattern and the adjacent surface of the sheet or layer and acts to cut off from said surface the portions thereof which are projected into the molds, to form a design in said surface.

The knife referred to may and preferably will be an endless belt knife having curved or inclined sides of different length to form a cutting edge which is located below the center or medium line of the knife, as will be described, so that a thin cutting edge is obtained, which is capable of being set at or in close proximity to the point of greatest compression of the fibrous sheet or layer, and so that said cutting edge also acts as a closure for the molds, and also as a glazing, calendering or ironing instrument for the cut portions of the surface of the fibrous sheet or layer, whereby the portions of the surface from which said cut portions are severed and which form the design, are ironed or calendered so as to bring out the design in marked contrast to the uncut portions of said surface.

These and other features of this invention will be pointed out in the claims at the end of this specification.

Figure 1 represents in section a sufficient portion of a machine embodying this invention to enable it to be understood. Fig. 2, a modification to be referred to. Fig. 3, a detail of a sheet or layer provided with one form of design, which may be produced on the machines shown in Figs. 1 and 2. Fig. 4, an enlarged detail in section of the knife preferred by me.

Referring to Fig. 1, *a* represents a pattern, which is formed in the circumference of a roll *b* of metal, hard rubber or other solid material, and which is shown as riding upon and rotated by contact with a large roll *c*.

Above the pattern roll *b* with its axial center in vertical line with the axial center of the pattern roll *b* is a pressure roll *d*, which is separated from the pattern roll by a sufficient space to permit a sheet or layer *e* of fibrous material to be fed under compressor between the said rolls, so as to force or project portions of the under surface 10 of the sheet or layer *e* into the molds, recesses or wells *a* in the circumference of the pattern roll, said molds or recesses forming a pattern.

The portions of the surface 10 which are forced under compression into the molds *a*, are confined therein against lateral movement by the walls of the mold and are therefore solidly supported, while they are cut off by the cutting edge of a knife 12, preferably a traveling belt or band knife movable between suitable guides 13 and which is arranged with relation to the pattern roll, so that its cutting edge is interposed between the said roll and the surface of the sheet or layer adjacent thereto, which in the arrangement shown in Fig. 1, is the under surface 10 of said sheet or layer.

The cutting edge of the knife is preferably made by curved, beveled or inclined surfaces of unequal length, the upper bevel or curve, 14 being longer than the bevel or curved surface 15 (see Fig. 4), so that the cutting edge is below the medium line 16 of the knife, whereby a sharp, thin cutting edge is obtained, which is capable of being carried forward between the rolls *b*, *d*, to or in close proximity to the vertical line through the axial centers of the said rolls, at which

point the fibrous sheet or layer *e* is subjected to the greatest compression, and the cutting edge acts tangentially with relation to the pattern and severs the portion of the sheet or layer which is projected from the under surface thereof into the mold, which is brought into the line of greatest compression, said cutting edge forming a closure for said mold as the pattern is moved toward the knife, and the upper beveled surface of said cutting edge also serving to iron, glaze or calender the cut portion of the under surface of the sheet or layer, whereby the design formed by the cut portion of the under surface is sharply defined with relation to the uncut portion of the same surface.

The longer beveled or curved surface 14 of the knife enables the cutting edge to be made thin, so as to be brought to or in close proximity to the point of greatest compression, while at the same time a substantially large clearance is obtained between the upper roll *d* and the knife for the free passage of the sheet or layer, and also to avoid contact of the upper roll with the knife.

The shorter beveled or curved surface enables the knife to be of sufficient thickness at or near the cutting edge, to obtain the desired strength in the knife at the cutting edge so as to avoid breaking of the same.

In Fig. 1, the pattern is shown in the roll *b*, which is located below the fibrous sheet or layer *e*, but it is not desired to limit the invention in this respect, as the pattern may be located above the sheet or layer and may be separate from its backing roll, as shown in Fig. 2, wherein the molds *a* are shown as formed in a strip or piece 20, which may be made of celluloid, metal or other suitable material, and the backing roll *b* is made plain and engages the upper surface of the pattern strip.

The machine herein shown is especially adapted for forming a design in a surface of a sheet or layer of material composed of fibers of different grades or kinds, such as a skin, or in the surface of a sheet or layer composed of the same kind or grade of fiber, such for instance as felt, and in the case of the latter, the design is sharply defined by the cut portions of the surfaces, whose fibers 30, Fig. 3, are ironed, calendered and compacted to give a materially firmer and distinguishable appearance than the uncut portion 31 of the surface.

Claims—

1. A machine for the purpose specified comprising a pattern roll provided on its

surface with a plurality of wells or recesses forming molds, a pressure roll coöperating with said pattern roll, to force portions of one surface of a sheet or layer of fibrous material into said molds, and a knife having inclined sides of unequal length which form a substantially thin cutting edge extended between said rolls to substantially the point of greatest compression and forming a closure for the mold near the point of greatest compression, substantially as described.

2. A machine for the purpose specified, comprising a movable pattern surface having a plurality of wells or recesses forming molds, a pressure member coöperating with said movable pattern to force portions of a fibrous sheet or layer into said mold, and a knife having inclined sides of different length to form a thin, cutting edge which is arranged to close the mouth of the mold and cut off from the surface of a sheet or layer of fibrous material the portion thereof which is projected into the mold at or near the point of greatest compression, substantially as described.

3. A machine for the purpose specified, comprising a movable pattern surface having a plurality of wells or recesses forming molds, a pressure member coöperating with said movable pattern to force portions of a fibrous sheet or layer into said molds, and a knife having a short and a long side forming a cutting edge, the longer side extending below the median line of the knife to form a thin cutting edge which forms a closure for the mouth of the molds, substantially as described.

4. A machine for the purpose specified, comprising a movable pattern surface having a plurality of wells or recesses forming molds, a presser member coöperating with said movable pattern to force portions of a fibrous sheet or layer into said molds, and a knife having a substantially thin cutting edge interposed between said pattern surface and the surface of the sheet or layer whose portions are forced into the molds and extended to substantially the point of greatest compression and forming a closure for the mold near the point of greatest compression.

In testimony whereof, I have signed my name to this specification in the presence of two subscribing witnesses.

FREDERICK W. MOORE.
